FLASHLIGHT

Henry Wirz, Long Beach, Calif.

Application January 9, 1945, Serial No. 572,027

4 Claims. (Cl. 240—10.5)

This invention relates to a flashlight.

The general object of the invention is to provide a novel portable hand flashlight which includes a generator and a pneumatic motor for driving the generator to thereby produce current for energizing a lamp bulb.

A more specific object of the invention is to provide a flashlight including a pneumatic motor and generator operated thereby and wherein the flashlight casing includes a storage receptacle for compressed air and a pump for introducing air under pressure into the chamber.

Another object of the invention is to provide a novel flashlight including means for supplying compressed air to a pneumatic motor in the flashlight casing.

Other objects and the advantages of the invention will be apparent from the following description taken in connection with the accompanying drawing, wherein:

Fig. 1 is a front view of a flashlight embodying the features of my invention;

Fig. 2 is a central, sectional view taken on line 2—2, Fig. 1;

Fig. 3 is a transverse section taken on line 3—3, Fig. 2;

Fig. 4 is an enlarged sectional view of the piston and associated parts;

Fig. 5 is a section taken on line 5—5, Fig. 2;

Fig. 6 is a side elevation showing a modification, and

Fig. 7 is a fragmentary, sectional view showing another type of piston head.

Referring to the drawing by reference characters, I have shown my invention as embodied in a flashlight which is indicated generally at 10.

As shown, the flashlight includes a casing or body 11 which comprises an intermediate portion 12, a front portion 13 and a rear portion 14. The intermediate portion 12 is shown as rectangular in cross section and as having a lower externally threaded cylindrical collar 16. The portion 14 has a transverse bore 17 which is closed at one end as at 18. In the bore 17 I arrange a piston 19.

Beyond the bore 17 I provide a cylindrical rotor cavity 20 (Fig. 3) which has diametrically arranged slots 21 and 22 in which nozzles 23 and 24 are arranged. In the cavity 20 I arrange a rotor or impeller 25 which has a shaft 26, the lower end of which seats in a recess 27.

Beyond the rotor 25 I provide a chamber 28 in which a generator 29 is mounted on the shaft 26 and is driven by the shaft. The upper end 30 of the shaft is shown as arranged in a hole 31.

in a closure member 32 which engages a flange 33 on the upper end of the intermediate portion 12. The closure 32 is held in place by screw 33'.

The closure 32 is a part of the front portion 13 which includes a casing 34 secured to the closure 32. In the casing 34 I arrange a reflector 35 and a lamp socket 36 which supports a lamp 37. The casing 34 further includes a lens member 38. One side of the lamp is grounded to the reflector 35 which is connected by a lead 39 to one pole of the generator. The other side of the lamp is connected to a contact 40 which in turn is connected by a lead 41 with the other pole of the generator.

The piston 19 includes a piston rod 45 which has a head 46 held in place by nuts 47 and 48. On the head 46 I arrange packing member 49. The head 46 includes a hole 50 in which a valve housing 51 is arranged. The valve housing includes a seat 52 and a port 53. A ball 54 engages the seat 52 and is normally urged to its seat by a spring 55 which is held in place by a threaded closure 56 which latter has a passageway 57 therethrough.

The portion 12 includes a boss 60 which has a valve bore 61 communicating with a passage 62. Flow through the passage 62 is controlled by a ball 63 normally urged against a valve seat 64 by a spring 65 which is held in place by a threaded plug 66 having a hole 67 therethrough.

From the cylinder 20 an outlet conduit 70 extends. This conduit 70 communicates through a pipe 71 with the nozzle 23 previously mentioned.

The collar 16 on the intermediate portion 12 threadedly engages a compressed air tank 75 which is threaded as at 76 on its lower end to support a cap 77 in which spare bulbs 78 may be placed.

The hole 67 communicates with the interior of the tank and forms an inlet for compressed air. The outlet for the tank 75 consists of a conduit 80 (Fig. 5) which extends through the body of the intermediate portion 12 and which communicates with the nozzle 24 previously mentioned.

The piston rod passes through a closure 81 which has an air inlet hole 82. The piston rod 45 includes a push member 85 which is normally urged outwardly by a spring 86.

In operating my improved flashlight, the user grasps the flashlight in his hand and pushes the member 85 inwardly and repeats this operation. This causes air in the cylinder during the intake

stroke to enter the port 53 and then on the compression stroke to be compressed and to pass through the conduit 70 and to be ejected through the nozzle 23 so that it strikes the blades of the impeller 25. The conduit 70 is sufficiently small so that all of the compressed air does not pass therethrough and is forced to escape through the passage 62 by the ball valve 63 and into the tank 18. The compressed air in the tank passes through the conduit 80 to the nozzle 24 which directs it against the impeller 25.

The size of the conduit 80 is such that the compressed air will gradually pass therethrough and will thus supply air to the nozzle 24. This will tend to prevent undue slowing down of the impeller during the retraction of the piston.

The impeller drives the generator 29 and this in turn supplies current through the leads 39 and 41 to thereby light the bulb 37.

In Fig. 6 I show a modification of my invention wherein the push member 85 is omitted and the piston rod 45' is pivotally connected at 90 to an operating arm 91 which is pivotally mounted at 92 on the closure 77'. A spring 93 normally urges the arm 91 outwardly. Except for the manner in which the piston rod 45' is actuated, the apparatus shown in Fig. 6 does not differ from that previously described.

In Fig. 7 I show another type of piston head which is indicated at 48'. This head is arranged on the piston rod 45', the forward end of which is reduced and threaded as at 92 to provide a shoulder 93 upon which a metal washer 94 is seated. A leather cup washer 95 engages the washer 94 and is held in place by metal washer 96 which latter is engaged by a nut 97 on the metal portion. The piston head shown in Fig. 7 does not offer any resistance on the rearward stroke and as soon as slight pressure is put on the washer 95 the latter is sealed.

From the foregoing description it will be apparent that I have invented a novel flashlight which is simple in construction and dependable in use and which can be economically manufactured.

Having thus described my invention, I claim:

1. In a flashlight, a body including a portion having a tank member thereon, said body including a cylinder, a piston slideable in said cylinder, said piston having a one-way valve thereon permitting flow to the portion of the cylinder in advance of the piston, a rod on said piston, a push member on said piston rod, spring means normally urging said piston in one direction, a one-way valve communicating with said cylinder and opening into said tank, said body including an impeller cavity, an impeller in said cavity, a pair of nozzles, conduit means communicating with the cylinder and with one of said nozzles, other conduit means affording communication between the other nozzle and the tank, a generator driven by said impeller, a lamp socket on said body, and a pair of leads for supplying current to said lamp socket, said leads being connected to the generator.

2. In a flashlight, a body including an intermediate portion, a tank member on said intermediate portion, a cylinder in said intermediate portion, a piston slideable in said cylinder, said piston having a one-way valve thereon permitting flow to the portion of the cylinder in advance of the piston, said cylinder having a closure, a rod on said piston, said closure having

an air inlet hole therein, said cylinder closure having an aperture through which said piston rod projects, a push member on said piston rod, spring means normally urging said piston in one direction, a one-way valve communicating with said cylinder and opening into said tank, said intermediate portion including an impeller cavity, an impeller in said cavity, diametrically opposed nozzles adjacent to said impeller, conduit means communicating with the cylinder and with one of said nozzles, other conduit means affording communication between the other nozzle and the tank, a generator adjacent to said impeller and driven thereby, a closure on the front portion of said intermediate member, said closure having a reflector therein, a lens in advance of said reflector, a lamp socket arranged in said reflector, a lamp in said socket, and a pair of leads for supplying current to said lamp, said leads being connected to the generator.

3. In a flashlight, a body including an intermediate portion which has a peripheral threaded collar on the rear end thereof, a tank member threadedly engaging said collar, said intermediate portion having a cylindrical bore therein, a piston slideable in said bore, said piston having a one-way valve thereon permitting flow to the portion of the bore in advance of the piston, said bore having a closure, a rod on said piston, said closure having an air inlet hole therein, said bore closure having an aperture through which said piston projects, a push member on said piston rod, spring means normally urging said piston rod in one direction, a one-way valve communicating with said cylinder and opening into said tank, said intermediate portion including an impeller cavity, an impeller in said cavity, diametrically opposed slots adjacent said impeller, a nozzle in each of said slots, conduit means communicating with the bore and with one of said nozzles, other conduit means affording communication between the other nozzle and the tank, a generator adjacent to said impeller and driven thereby, a closure on the front portion of said intermediate member, said closure having a reflector therein, a lens in advance of said reflector, a lamp socket arranged in said reflector, a lamp in said socket, and a pair of leads for supplying current to said lamp, said leads being connected to the generator.

4. A flashlight including an elongated body having a tank member thereon, said body including a cylinder, the axis of said cylinder extending transversely of the body, a piston slideable in said cylinder, said piston having a one-way valve thereon permitting flow to the portion of the cylinder in advance of the piston, a rod on said piston, a push member on said piston rod, spring means normally urging said piston in one direction, a one-way valve communicating with one end of said cylinder and opening into said tank, said body including an impeller cavity, an impeller in said cavity, a pair of nozzles disposed in opposed relation at opposite sides of the impeller, conduit means communicating with the other end of the cylinder and with one of said nozzles, other conduit means affording communication between the other nozzle and the tank, a generator driven by said impeller, a lamp socket on said body and a circuit connecting the lamp socket to the generator.

HENRY WIRZ.
